[57] CLAIM

The ornamental design for a heelrest for motorcycles,
as shown.

DESCRIPTION

FIG. 1 is a top, rear and right side perspective view of
a right side heelrest for motorcycles showing my new
design;FIG. 2 is a side elevation view as seen from left to right;
FIG. 3 is a side elevation view as seen from the side
opposite that shown in FIG. 2;

FIG. 4 is a top plan view thereof;

FIG. 5 is a bottom plan view thereof;

FIG. 6 is a rear view thereof;

FIG. 7 is a rear elevational view thereof, the heelrest
having been rotated 180 degrees with the heelrest cushion
repositioned to provide a heelrest for the left side of
a motorcycle; and,FIG. 8 is a top, rear and opposite side perspective view
of that shown in FIG. 1 and of a left side mounted
heelrest as shown in FIG. 7.*Fig. 1**Fig. 2**Fig. 3*
